(57) **CLAIM**

The ornamental design for a beverage dispenser as shown and described.

DESCRIPTION

FIG. 1 is a front/right/top perspective view of a beverage dispenser showing my design;

FIG. 2 is a front elevation view thereof;

FIG. 3 is rear elevation view thereof;

FIG. 4 is a left side elevation view thereof (a right side elevation would be a mirror image thereof);

FIG. 5 is a top plan view thereof; and,

FIG. 6 is a bottom plan view thereof.

Dashed lines are used to show unclaimed structures.

1 Claim, 6 Drawing Sheets
